UNITED STATES PATENT OFFICE.

MORITZ RHEINAUER, OF NEW YORK, N. Y.

DESIGN FOR A BOTTLE.

SPECIFICATION forming part of Design No. 33,214, dated September 18, 1900.

Application filed August 27, 1900. Serial No. 28,259. Term of patent 7 years.

To all whom it may concern:

Be it known that I, MORITZ RHEINAUER, a citizen of the United States, and a resident of the city of New York, borough of Manhattan, in the county and State of New York, have invented and produced a new and original Design for a Bottle, of which the following is a full, clear, and exact description.

Reference is to be had to the accompanying drawings, forming a part of this specification, in which similar characters of reference indicate corresponding parts in both the figures.

Figure 1 is a perspective view of a bottle, showing my design; and Fig. 2 is a top view.

The leading feature of my design for a bottle consists in the body having two of its opposite side walls V-shaped or forming two

lines of a triangle, with the apex inward and extended throughout the length of the body. The other two opposite sides of the body are shown as flat, and a projection on one end of the body has a thread-like exterior.

Having thus described my invention, I claim as new and desire to secure by Letters Patent—

The design for a bottle, as herein shown and described.

In testimony whereof I have signed my name to this specification in the presence of two subscribing witnesses.

MORITZ RHEINAUER.

Witnesses:

JNO. M. RITTER,
C. R. FERGUSON.
